UNITED STATES PATENT OFFICE

168,139

BACK REST

Francis J. Brady, Goulds, Fla.

Application December 16, 1949, Serial No. 6,679

Term of patent 14 years

(Cl. D3—9)

To all whom it may concern:

Be it known that I, Francis J. Brady, a citizen of the United States, residing at Goulds, county of Dade, State of Florida, have invented a new, original, and ornamental Design for Back Rest, of which the following is a specification, reference being had to the accompanying drawing, forming a part hereof.

Fig. 1 is a side view of the back rest, showing my new design.

Fig. 2 is a plan view.

Fig. 3 is a perspective view, the top and bottom side edges being reversed with respect to Fig. 2.

Fig. 4 is an end view of that shown in Fig. 2, and

Fig. 5 is a section on line 5—5, Fig. 2, with that portion of the back rest to the left of such line being seen in angular perspective.

I claim:

The ornamental design for back rest, as shown.

FRANCIS J. BRADY.
